UNITED STATES PATENT OFFICE.

ALBERT A. KELLOGG, OF KANSAS CITY, MISSOURI.

CHEMICAL FIRE EXTINGUISHER.

Application filed January 29, 1923, Serial No. 615,654. Renewed January 20, 1925.

To all whom it may concern:

Be it known that I, ALBERT A. KELLOGG, a resident of Kansas City, in the county of Jackson and State of Missouri, a citizen of the United States, have invented certain new and useful Improvements in Chemical Fire Extinguishers, of which the following is a specification.

My invention relates to improvements in chemical fire extinguishers particularly constructed and adapted for service in office buildings, warehouses, apartments, vessels and other character of structures comprising a number of separate rooms, although my invention may be used in any situation where it would operate in a reliable and effective manner.

One object of my invention is the provision of an apparatus of the character stated which instantly upon the breaking out of a fire at a certain place, the mechanism will operate to immediately extinguish the fire without damage to any other locality than where the fire originates.

Another object of my invention is the provision of a chemical fire extinguisher which will operate instantly to extinguish the fire, and which will insure the proper mixture of chemicals with the water to produce the most efficient fire extinguishing fluid.

Another object of my invention is the provision of a chemical fire extinguisher which will be automatic, instant and practical in operation; which will be composed of comparatively few parts to insure simplicity, durability and cheapness of construction; which will be compact and small in size to occupy a small space; and which generally in every particular will be efficient, reliable and practical.

With these objects in view, my invention consists of a chemical fire extinguisher embodying novel features of construction and combination of parts, substantially as disclosed herein, it being understood that any changes may be made in the construction of the apparatus which come within the scope of the claims.

In order that the construction in detail and the operation of my extinguisher may be fully understood and its many advantages and features of merit be appreciated, I have shown in the accompanying drawings a chemical fire extinguisher construct-

ed according to the best principles I have so far devised, and in said drawings:

Fig. 1 represents a complete fire extinguisher embodying my invention shown in perspective.

Fig. 2 represents a view partly in perspective and partly broken away of the chemical tanks, valve mechanism and supply container of my invention, for purpose of clearness the view being enlarged.

Fig. 3 represents a vertical longitudinal sectional view of the chemical tanks, the supply container, the valve mechanism in said container, and the valve mechanism associated with said chemical tanks, the view being on an enlarged scale taken on line 3—3 of Fig. 5.

Fig. 4 represents a side elevation of the chemical tanks, valve operating mechanism, supply container, and gearing and mechanism operated in connection therewith, and

Fig. 5 represents a sectional view on the line 5—5 of Fig. 4.

Referring by numeral to the drawings, in which the same numerals of reference are used to denote similar parts in all the views:

The numeral 1 designates a platform or base upon which the entire mechanism comprising my chemical fire extinguisher is supported and which is of the desired size according to the capacity of the machine, and upon this base is secured the motor 2, upon whose shaft 3, is mounted a driving gear wheel 4, which meshes with the large gear wheel 5 on the shaft 6, of the pump 7, which is connected with the delivery pipe 48, which directs the mixed chemically charged liquid to the pump for the purposes of discharging said charged liquid for extinguishing the fire.

In use the motor is connected in circuit with a sprinkling system of any desired character operated electrically, and instantly upon the fire occurring at any place in the sprinkler system, the circuit will be closed which will operate the motor to drive the pump and force the extinguishing liquid through the pipe to the proper point, as will be readily understood.

Mounted upon the base or platform 1 and in parallel relation to the motor and pump 105 is the supporting structure or framework 9, which rises from the supply tank or container 10, which is of the desired size and

is connected to the delivery pipe by means of the branch pipe 11, in which is located the rotary valve 12, the operation of which will presently appear, and arranged above the supply tank and supported upon the frame are the chemical containers 13 and 13', which contain a suitable chemical which will mix with water to produce the necessary extinguishing fluid, and leading from the bottoms 14 and 14', of said containers are the outlets 15 and 15', from which depend and discharge into the supply tank the branch pipes 16 and 16', thus in a manner to be described, feeding the chemical from the pair of tanks directly into the supply tank, where it mixes with the water therein to provide the chemical fluid for extinguishing the fire.

The discharge pipes or branches are provided, the pipe 16 with the couplings 17, in which are seated the rotary valves 18, while the pipe 16' is provided with seats 19, for the gate or slide valves 20, the valves being operated by a novel mechanism which I will now describe.

The shaft of the motor carries a small gear wheel 21, which meshes with the gear wheel 22, operating a train of gearing consisting of gear wheel 23, which meshes and drives gear wheel 24, which drives gear wheel 25, all on the series of studs mounted in the inclined bar or frame 28, and the rotation of gear wheel 25, meshing with gear wheel 26, connected to pin 29, engaging slot 30, in pivoted lever 31, oscillates said lever, causing the upper slotted end 32 thereof, to engage the pin 33, carried by the depending arm 34, of the yoke 35, to reciprocate said yoke, in its guides 36, said yoke carrying lateral pins 37, which move slotted arms 38, on the pair of rotary valves 18, to open one valve and close the other simultaneously, as shown in Fig. 3, and said yoke is further provided with vertical pins 39, which engage slotted levers 40, on the valves 20, to open one and close the other of said valves, the upper of said valves 20, being provided with a series of arms 41, which provide an agitator for assisting in the proper stirring or mixing of the chemical.

From this construction it will be noted that motion is transmitted from the gear wheel on the motor shaft to the train of gearing, and that the lever associated with said train of gearing is given a reciprocating or rocking action, the effect of which is to move the yoke back and forth in a horizontal direction and simultaneously open and close one rotary valve and one slide valve, of the chemical supply tanks, the purpose of which is to discharge at regular intervals the necessary and determined amount of chemicals into the water of the supply tank, which is provided with the inlet controlled by the float valve 42, which permits the

water to flow into the tank, and to automatically operate the controlling valve of the inlet pipe, I provide the lever 43, which is connected to the valve at 44, and from which leads the rod or pitman 45, to the pivoted lever 46, which is engaged upon the starting of the machine by the cam or eccentric 47, operated by the motor through the train of gearing, to immediately move the lever and open the valve to the position shown in dotted line.

From the foregoing description, taken in connection with the drawing, the operation of my invention will be so apparent that further elaboration thereof is deemed unnecessary, and it will be understood that the chemical tanks are properly charged with the most suitable chemical for the purpose, and that the supply tank which is in communication with said chemical tanks is supplied with the proper amount of water, and that instantly upon the starting of the motor, the train of gearing is set in motion to operate the force pump and simultaneously the valve mechanism associated with the chemical tanks and supply tanks to insure the proper supply and mixture of the chemically charged fluid and the completion of the delivery of this fluid to the point where the fire has started to instantly and automatically extinguish such fire.

In the operation of my fire extinguisher the water under service pressure is supplied to the inlet pipe 8 which leads to the water supply tank 10 and the amount of water in said tank is regulated by the float valve, as shown most clearly in Fig. 3, to retain at all times the full amount of water necessary for supply through the feed pipe 48, leading from the tank to the pump 7, and leading from the pump 7 is the discharge or outlet pipe 49, which pipe is preferably connected to the sprinkling system of any character, and instantly upon the starting of the motor the water is pumped from the pump through the discharge or outlet pipe to the place where the fire has started, as will be clearly understood by reference to the drawings and description.

I claim:

1. A chemical fire extinguisher, consisting of chemical supply means, a mixing fluid means associated with said chemical supply means, a valve mechanism for controlling the supply from the chemical supply to the mixing fluid means, and automatically operated mechanism for controlling said valve mechanism, said valve mechanism consisting of two sets of valves, operated one to open and the other to close, means carried by said valves to operate them, and means for operating said means simultaneously.

2. A chemical fire extinguisher, consisting of a motor, a pump associated with and operated by said motor, a water supply

tank, an inlet pipe leading to said tank, a valve mechanism controlling said inlet pipe and operated by said motor, chemical supply tanks associated with said water supply tank 5 and discharging thereinto, a valve mechanism for controlling the discharge from the chemical tanks to said water-supply tank and operated from said motor.

3. A chemical fire extinguisher, consisting 10 of a water tank or container, an inlet pipe connected with said container, a controlling valve for said inlet pipe, a controlling valve for said container, a pump in communication with said container, a dis-

charge leading from said pump, a motor 15 for operating said pump, chemical tanks for supplying chemicals to said water container, and a valve mechanism for controlling the supply of chemicals to said container and operated from said motor, said valve mechanism consisting of two sets of valves operated one to open and the other to close, means carried by said valve to operate them, and means for operating said means simultaneously. 20

In testimony whereof I hereunto affix my signature.

ALBERT A. KELLOGG.
